ATTORNEY.

UNITED STATES PATENT OFFICE.

ARTHUR KIRKLAND, OF DETROIT, MICHIGAN.

GRINDING MACHINE.

1,410,761.

Specification of Letters Patent. Patented Mar. 28, 1922.

Application filed June 10, 1921. Serial No. 476,438.

To all whom it may concern:

Be it known that I, ARTHUR KIRKLAND, citizen of the United States, residing at Detroit, county of Wayne, State of Michigan, have invented a certain new and useful Improvement in Grinding Machines, and declare the following to be a full, clear, and exact description of the same, such as will enable others skilled in the art to which it 10 pertains to make and use the same, reference being had to the accompanying drawings, which form a part of this specification.

My invention relates to a grinding machine and a special object of my improvements is to provide an improved machine for grinding cylindrical machine parts that shall be simple and compact. I accomplish this object in the device illustrated in the accompanying drawing in which:

20 Figure 1 is a side elevation partly broken away of an apparatus embodying my invention.

Fig. 2 is an end elevation of the same looking from the right of Fig. 1.

25 Fig. 3 is a detailed view to an enlarged scale.

a is the base of the machine. Upon this base is mounted a standard x carrying a shaft b which shaft may be rotated by an 30 electric motor or any suitable source of power. c and d are pulleys fixed upon the shaft b.

e is a standard adjustably mounted upon the base a and carrying bearings e² e² at its 35 upper portion. f is a grinding wheel secured upon a rotatable shaft f² which shaft rests and rotates in the bearings e² e². f³ is a pulley upon the shaft f. cf is a belt passing over the pulley c and f³.

40 g is a standard or support rising from the base a and provided with an interior roller bearing g². h is an annular wheel which I make of the same material as the grinding wheel f so that it may firmly engage the work to move the same. This is fixed to a carrier ring h² which ring is adapted to be 45 inserted and fixed in the bearing g². h³ is a pulley connected with the carrier ring h² so as to rotate the same. dh is a belt around 50 the pulley d and the pulley h³. d³ is a rider pulley adapted to maintain the tension of the belt dh.

The standard x may be made adjustable so as to regulate the tension upon the belt cf. 55 In Fig. 2 the broken line CLf indicates

the center line of the pulley f and shaft f², and CLh indicates the center line of the annular wheel h and carrier ring h². It will be noted that there is a slight angle between these center lines. 60

The grinding wheel f is located within the annular wheel h.

j is a holding apparatus.

m is the work rest bar. This bar is supported and positioned by resting in the holder j. The bar m is octagonal in cross section.

k is the cylindrical piece to be ground. This is placed between the interior wall of the annular wheel h and the periphery of 70 the grinding wheel f and is supported upon one of the surfaces of the work rest.

The power is imparted to the shaft b to rotate the same and thus through the pulleys c and d and belts cf and dh rotating the 75 grinding wheel f rapidly in one direction and the annular wheel h at a much lower rate in the opposite direction. The annular wheel h rotates and feeds the work k while the grinding wheel f grinds its surface 80 smooth and accurate.

Inasmuch as the contacting surfaces between the work k and the annular wheel h curve in the same direction, a firm hold is obtained by the annulus h to rotate the work 85 k, while the contacting surfaces of the work and the grinding wheel f move in opposite directions and a good grinding effect is obtained.

The shaft of the holding bar m affords 90 a number of holding surfaces. If one surface becomes injured or abraded the bar is rotated about its axis to bring another surface in position to receive the work k. The bearing g for the annular wheel h is 95 large and assures a firm and rigid support, moreover, it is in the same plane as the points of contact with the work k.

The rapidly rotating grinding wheel f is enclosed so that safety to the operator is 100 secured.

Claims:

1. In a grinding machine, the combination of a grinding wheel, and an annular wheel, the first named wheel being located 105 within the annular wheel, the parts being located so as to receive the work between the periphery of the first named wheel and the inner wall of the annular wheel and operate upon said work.

2. In combination with the apparatus of claim 1, a bearing of greater diameter than the opening in said annular wheel, said annular wheel resting in said bearing, nular wheel resting in said bearing, said bearing being in the plane of contact between the work and the parts operated thereon.
- 5 3. In combination with the apparatus of claim 1, a bearing of greater diameter than the opening in said annular wheel, said an- In testimony whereof, I sign this specification.

ARTHUR KIRKLAND.
